UNITED STATES PATENT OFFICE.

JAMES J. O'SHEA, OF ST. LOUIS, MISSOURI.

IRONING-MACHINE.

SPECIFICATION forming part of Letters Patent No. 741,269, dated October 13, 1903.

Application filed July 30, 1902. Serial No. 117,697. (No model.)

To all whom it may concern:

Be it known that I, JAMES J. O'SHEA, a citizen of the United States, residing at the city of St. Louis, in the State of Missouri, have invented a certain new and useful Ironing-Machine, of which the following is such a full, clear, and exact description as will enable any one skilled in the art to which it appertains to make and use the same, reference being had to the accompanying drawings, forming part of this specification.

My invention relates to certain improvements in ironing-machines for ironing shirt-waists, such as are described in Letters Patent No. 700,439, granted to me May 20, 1902.

My invention consists in part in the combination, with a rotary iron having its working face at right angles to its axis, of an ironing-board, said board being provided with a convex face and said iron being provided with a corresponding concave face.

My invention also consists in part in the combination, with a rotary iron having its working face at right angles to its axis, of an ironing-board and an arm carrying said ironing-board, said arm being downwardly curved to leave an open space for the passage of the goods in the machine.

In the accompanying drawings, which illustrate one form of machine made in accordance with my invention, Figure 1 is a side elevation. Fig. 2 is an enlarged sectional view of the iron, and Fig. 3 is an enlarged sectional view of the table.

Like marks of reference refer to similar parts in the several views of the drawings.

5 is the upright or standard, which is carried upon a suitable base 6. Extending from the upper part of the standard 5 is an arm 7, 40 which carries the rotary iron 8. The iron 8 is protected by means of a hood 9, as shown in Fig. 1.

11 and 12 are loose and fast pulleys by means of which the rotation of the iron 8 is controlled. The movement of the fast pulley 45 12 is transmitted to the iron 8 by means of suitable shafting and gearing within the arm 7 and a gear-case 14, carried at the end of said arm. The working face 15 of the iron 8 is 50 made concave, as is clearly shown in Fig. 2.

Situated below the iron 8 is the ironing board or table, which consists of a base 17, a layer of hard rubber 18, a layer of felt 19, and a flexible cover 20, which forms the working face of the table. The flexible covering 20 is 55 held in position by means of pins 21 on the base 17. The pins 21 are protected by means of a shield 22.

As will be readily seen from the drawings, the face of the ironing-board is convex, corresponding to the concave face 15 of the iron 8. The ironing-board 20 is raised into contact with the iron 8 by means of a treadle 24, the motion of which is communicated to said board by means of a rod 25 and lever 26. 60

The ironing-board is carried by means of an arm 27, projecting from the column or standard 5. This arm 27, instead of projecting straight from the standard to the table, is downwardly curved, as clearly shown in Fig. 70 1, thus leaving an open space for the passage of the goods hanging down around the table.

By making the faces of the iron and table concave and convex, respectively, in place of flat I find that the machine is much more effective for ironing shirt-waists and similar articles. The form of the arm 27 also prevents the goods from coming in contact with said arm, and thus being soiled. 75

Having fully described my invention, what I claim as new, and desire to secure by Letters Patent of the United States, is—

1. In an ironing-machine, the combination with a rotary iron having a cup-shaped working face at right angles to its axis, of an ironing-board having a corresponding convex working face. 85

2. In an ironing-machine, the combination with a rotary iron having a concave spherical working face at right angles to its axis, of an ironing-board having a corresponding convex working face. 90

In testimony whereof I have hereunto set my hand and affixed my seal in the presence of the two subscribing witnesses.

JAMES J. O'SHEA. [L. S.]
